LAMP SHADE OR THE LIKE

Gwendoline A. Bryant, High Wycombe, England

Application September 13, 1944, Serial No. 553,830
In Great Britain September 11, 1943

2 Claims. (Cl. 240—108)

This invention relates to lamp shades or the like, and has for its object the provision of an improved lamp shade or the like which will have a highly attractive and decorative appearance.

In accordance with the invention the covering of the shade or the like, or a part thereof, is made of two layers of light transmitting material having sandwiched between them one or a number of waved ostrich feathers. The rear layer—that is the layer nearest the lamp—may be of a coloured fabric or other material which is sufficiently thin to transmit light, and the front layer may be of a plain, transparent, preferably non-inflammable, flexible material. The effect of the coloured light passing from the inner coloured layer through the ostrich feathers is highly attractive and pleasing to the eye.

Lamp shades in accordance with the invention may be made in all shapes. Wire frames with soldered joints are first provided and completely bound with ribbon, and the covering is then applied. All the outside edges may be bound with silk cord or silk velvet ribbon.

Although ostrich feathers are preferred, the invention is not limited to ostrich feathers but other feathers might in some instances be employed.

In order that the invention may be the more clearly understood two examples of lamp shades in accordance therewith will now be described, reference being made to the accompanying drawing, wherein:

Figure 1 is a perspective view of one of said examples;

Figure 2 is a cross section of the same looking from the right hand end of Figure 1;

Figure 3 is a perspective view of a frame structure incorporated in the lamp shade of Figures 1 and 2;

Figure 4 is a perspective view of the other example.

Referring first to Figures 1 and 2, these illustrate a lamp shade of the type adapted to be mounted on the head of a bedstead. This type of lamp shade is, in general, in the form of a hollow cylinder with its circumferential wall cut away through part of the circumference, and it is adapted to be mounted on the top edge of the head of the bedstead, with its axis horizontal and transverse to the bed, and with the cut away portion downwards, so that light from the lamp inside the shade is thrown freely downwards on to the region of the pillow.

In the present arrangement, each of the walls of the lamp shade consists of an inner and an

outer layer of light transmitting material with ostrich feathers sandwiched between them. Thus the circumferential wall consists of an inner layer 2 and an outer layer 3 with waved ostrich feathers 4 sandwiched between, and each end wall consists of an inner layer 5, and an outer layer 6 with waved ostrich feathers 4 sandwiched between them. The inner layers 2, 5 are of some suitable tinted material, say rose coloured, and are thus only semi-transparent. The outer layers 3, 6 are of completely transparent material. The material for both the inner and the outer layers may be a suitable cellulosic material. The reference 4a designates the stalks of the ostrich feathers.

5 In construction the shade is built on to a skeleton frame illustrated in Figure 3 which may be made of wire bound with some soft tape-like material. This frame comprises two circular end rings 7 connected in coaxial spaced relation by means of back and front longitudinal members 8 and 9. The inner and outer end layers 5 and 6 are cut out in the form of discs adapted to fit outside the end rings 7 and are mounted on said end rings by sewing, an inner and outer disc being 10 of course mounted on each end ring. The inner and outer circumferential layers 2 and 3 are cut out in the form of rectangular blanks, and they are also mounted on the outside of the frame by sewing, each with one horizontal edge against the 15 front longitudinal member 9, the opposite horizontal edge against the back longitudinal member 8 and the other two edges respectively running around the upper portions of the end rings 7 between said members 8 and 9. Thus the lower 20 space between said members 8 and 9 forms the cut-away space of the circumferential wall of the shade.

The layers 2, 3, 5 and 6 are preformed with perforations near their edges through which the 25 stitches sewing them to the frame are passed. The reference 10 designates stitches securing the horizontal edges of the circumferential layers 2 and 3 to the members 8 and 9.

The frame structure also comprises a member 30 11 extending diametrically across one of the end rings 7 and carrying a small ring 12 which carries the socket for the lamp 1.

Said wire frame structure also incorporates the means whereby the lamp shade is adapted to 35 be mounted on the head of the bedstead. These means comprise vertical portions 13, extending downwardly from the points of junction of the rings 7 and the back member 8, and a horizontal portion 14 joining the lower ends of said vertical portions; also short horizontal portions 15 ex-

tending rearwardly from the back member 8 and a downwardly bowed portion 16 joining the ends of said portions 15. To mount the lamp shade in place, it is placed with the short members 15 across the top edge of the head of the bedstead, the members 13, 14 at the front and the member 16 at the back of said head.

It will be seen that the whole lamp shade is finished by decorative crinkled material 17 arranged as will be sufficiently clear from the drawing and secured by sewing to the frame structure.

Referring now to Figure 4, this illustrates the invention applied to a wall type of shade adapted to cover wall lamps of the elongated upright type. In this case, in the well known way, the shade is of more-or-less semi-cylindrical form as shown and is adapted to be mounted vertically against the wall covering the elongated upright lamp.

The shade consists of outer and inner layers of light transmitting layers as before with waved ostrich feathers sandwiched between them. These layers as before are sewn on to a wire frame, which in this case is very simple, consisting of a closed loop 18 shaped to conform to the edge of the lamp shade, and top and bottom circular rings 19 and 20 supported by members 21 and 22 from the upright members of said closed loop as shown, the lower and larger ring 22 being adapted to slide over, and the upper and smaller ring 21 to rest on the top of, the lamp bulb, so that the shade is supported by the lamp bulb

itself. As in the preceding example decorative material is sewn on to the frame and further description is not deemed necessary.

What I claim and desire to secure by Letters Patent is:

1. A lamp shade comprising a skeleton frame including a pair of circular end rings and front and back longitudinal members connecting said end rings in coaxial spaced relation, and a light transmitting wall of semi-cylindrical shape mounted on said skeleton frame and encompassing the area between said end rings and the upper space between said front and back longitudinal members and having a cut-away area for the passage of light in the lower space between said members, said light transmitting wall comprising two spaced layers of light transmitting material and waved ostrich feathers interposed between said layers with the stalks of said feathers extending longitudinally of said shade, said feathers occupying, substantially, the entire space between said spaced layers of light transmitting material, and the wave of said feathers extending in a direction transverse to the longitudinal axis of said shade.

2. A lamp shade as defined in claim 1, and each of said layers of light transmitting material having pre-formed stitch holes adjacent the edges thereof, and stitches connecting the end rings and said longitudinal members of said skeleton frame.

GWENDOLINE A. BRYANT.
